CLAIM

The ornamental design for a spout, as shown and described.

DESCRIPTION

FIG. 1 is perspective view taken from the top, front and left side of a spout showing our new design;

FIG. 2 is a left side elevational view thereof, the right side elevational view being the mirror image of the left side shown;

FIG. 3 is a front elevational view thereof;

FIG. 4 is a rear elevational view thereof;

FIG. 5 is the top plan view thereof;

FIG. 6 is a bottom plan view thereof;

FIG. 7 is an enlarged cross sectional view taken on line 7—7 of FIG. 2;

FIG. 8 is an enlarged cross sectional view taken on line 8—8 of FIG. 2;

FIG. 9 is an enlarged cross sectional view taken on line 9—9 of FIG. 2;

FIG. 10 is a left side elevational view of a second embodiment thereof, the right side being a mirror image of the left side;

FIG. 11 is a front elevational view of FIG. 10;

FIG. 12 is a rear elevational view of FIG. 10;

FIG. 13 is a top plan view of FIG. 10;

FIG. 14 is a bottom plan view of FIG. 10;

FIG. 15 is a left side elevational view of a third embodiment thereof, the right side being a mirror image of the left side;

FIG. 16 is a front elevational view of FIG. 15;

FIG. 17 is a rear elevational view of FIG. 15;

FIG. 18 is a top plan view of FIG. 15;

FIG. 19 is a bottom plan view of FIG. 15; and,

FIG. 20 is a left side elevational view of a forth embodiment thereof, the right side being a mirror image of the left side.
